2,562,290 A 7/1951 Dickerson
2,661,993 A 12/1953 Little
3,278,248 A 10/1966 Tibor
4,312,086 A 1/1982 Bianco

FIG. 1 is a front perspective view of the wall mounted storage system with drawers.

FIG. 2 is a front elevation view of the second embodiment of the drawer for a wall mounted storage system;

FIG. 3 is a rear elevation view of the second embodiment of the drawer for a wall mounted storage system;

FIG. 4 is a right side view of the second embodiment of the drawer for a wall mounted storage system;

FIG. 5 is a left side view of the second embodiment of the drawer for a wall mounted storage system;

FIG. 6 is a top plan view of the second embodiment of the drawer for a wall mounted storage system; and,

FIG. 7 is a bottom plan view of the second embodiment of the drawer for a wall mounted storage system.

The dot-dash lines represents boundaries to the drawer for wall mounted storage system and forms no part of the claimed design.

The broken lines shown in the figures represent portions of the drawer for wall mounted storage system that form no part of the claimed design.

The drawer for wall mounted storage system is shown with a symbolic break in its length. The appearance of any portion of the article between the break lines forms no part of the claimed design.

1 Claim, 5 Drawing Sheets
